COMBINATION SINK AND DISHWASHER

Wilbur S. Spitzer, Edenton, N. C.

Application February 4, 1946, Serial No. 645,294

2 Claims. (Cl. 134—115)

1

This invention relates to combination sink and dishwasher having juxtaposed compartments with means for spraying dishes from above and below in one of said compartments.

An object of this invention is to provide a sink that can be utilized as a work table, dishwasher or conventional sink.

Another object of the invention is to provide a dishwasher that can be easily installed in a sink with few minor alterations.

Another object of the device is to provide a dishwasher that is simple in operation and construction and can be easily positioned in the sink or removed therefrom.

With the above and other objects in view the invention consists of the novel details of construction, arrangement and combination of parts more fully hereinafter described, claimed and illustrated in the accompanying drawings in which:

Figure 1 is a sectional view of an embodiment of the invention.

Figure 2 is a top plan view with the cover in open position.

Figure 3 is a view of the dishwasher installed on a double sink.

Figure 4 is a sectional view on the line 4—4 of Figure 3.

Figure 5 is a modified form of the dishwasher and

Figure 6 is a sectional view on the line 6—6 of Figure 5.

Referring more in detail to the drawings the numeral 10 designates a sink in which an embodiment of the invention is installed as shown in Figure 1.

The sink 10 is provided with an inlet 12 adjacent the top of the sink below the drain board 14 and an inlet 16 adjacent the bottom of the sink. Couplings 18 are positioned in the inlets and gaskets 20 thereon provide water tight seals between the couplings and the sink. The couplings 18 are connected to a supply pipe 22 in the conventional manner by an elbow 24 and a T-coupling 26. The supply pipe 22 is connected to a water pump 28 which is driven by an electric motor 30.

The sink is provided with a drain 32 to which is connected a two way valve 34 which permits the water in the sink to be drained through the goose neck 36, permits water to flow to the pump 28 by means of the pipe 38 connected thereto or will close the drain, thus retaining the water in the sink.

The upper coupling 18 is provided with a coni-

2

cal seat 40 to receive the complimentary shaped coupling 42 which is connected to the center of the tubular member 44 which is positioned at right angles thereto. Longitudinally extending tubular members 46 having perforations 48 are connected to the member 44 at the outer ends thereof, the center thereof and intermediately of the center and outer ends as shown in Figure 2 and a bar 50 secured to the ends of the members closes these ends and forms the upper dishwasher frame 52.

The frame 52 is connected to a cover 54 by means of loop hangers 56 secured to the cover. The cover is hinged to the sink at 58 and is provided with a depending flange 60 to provide a water tight fit between the cover and the sink.

The lower coupling 18 is provided with a conical seat 40 to receive the complimentary shaped coupling 42 which is connected to the center of the tubular member 62 which is positioned at right angles thereto. Longitudinally extending tubular members 64 having perforations 48 are connected to the member 62 as are the members 46 and a bar 66, similar to bar 50 forms the lower dishwasher frame 68. The frames are similar except for the means of suspension within the sink. The frame 68 having thumb screws 70 positioned in the bar 66 which are received in seats 72 formed in the side of the sink adjacent the bottom thereof and when the screws are tightened the frame 68 is fixed in position as shown in Figure 2.

A wire basket 74 having feet 76 is positioned in the sink to hold the dishes during the washing thereof.

The cycle of operation of this device is as follows:

The sink is filled with hot water to a point below the lower frame, soap powder is added, the valve is turned to permit the water to circulate through the pump and supply pipe, the cover is closed, the motor started and the water is sprayed on the dishes in the wire basket, water descends from the upper frame and ascends from the lower frame. When the dishes are clean the motor is stopped, the valve is turned to drain the soapy water and clean water is added, the motor is again started, and the clean water is used to rinse the dishes. When the dishes have been thoroughly rinsed the water is drained and the dishes allowed to dry.

The construction as shown in Figure 3 is similar to the construction as previously described except that the washer is shown installed on a double sink 78 and the cover 54, instead of being

hinged is provided with ribs which are positioned in parallel recesses 80 whereby the cover is adapted to slide from one compartment to another.

A latch 82 is provided on the cover 54, which coacts with a keeper 84 on the sink.

In the modification shown in Figure 5, the coupling 42 is connected to the tubular member 86 and longitudinally extending tubular members 88 are connected to the ends thereof. A bar 90 connected to the free ends of the members 88 is provided with thumb screws 78 as is the lower frame 68 and the frame 92 thus formed is installed in the same manner as frame 68.

In this instance the members 88 are provided with vertically disposed and relatively spaced outlets 94 which are apertured at 96 and provided with collar flanges 98 on which are mounted the rotary tubular sprinklers 100, which are perforated at 102. The sprinklers are provided with the bearing 104 and bearing seat 106, and are retained on the outlets 94 by means of the screw 108.

The sprinklers 100 are similar to the conventional lawn sprinklers in shape and operation and a frame similar to the frame 92 can be attached to the cover 54 as is the frame 52.

The operation of this form of the invention is the same as previously described except that the water used to wash the dishes will be given a circulatory motion.

It is believed that the operation of the device will be apparent to those skilled in the art and it is to be understood that changes in the details of construction, arrangement and combination of parts may be resorted to without departing from the spirit of the invention or the scope of the appended claims.

Having thus described the invention what is claimed as new and desired to be secured by Letters Patent is:

1. An electric dishwasher attachment for a double compartment sink having a plurality of inlets in one of said compartments, comprising water supply means connected to said inlets, pump means interposed in said water supply means, a drain for said latter compartment of the sink, a two way valve connected to said drain, a connection between said two way valve and said pump means to provide circulating motion of water entering the last of said compartments, a coupling having a conical shaped seat therein connected to each of said inlets, a tubular frame positioned in the bottom of said last compartment, a coupling having a conical shaped projection thereon on said frame adapted to be removably connected to the conical seat on one of said inlets, means carried by said frame for supporting said frame in said last compartment, rotary tubular perforated spray members carried by said frame, a cover slidably mounted on said sink to selectively cover either compartment in said sink, a tubular perforated spray frame mounted on the underside of said cover, a coupling having a conical shaped projection thereon adapted to be removably connected to the conical shaped seat on another of the inlets in said last com-

partment, and a basket in said sink above said first tubular frame to support dishes therein for the washing thereof.

2. In a dishwashing sink, the combination which comprises a double sink having integral juxtaposed compartments, each having a bottom and upwardly extended side and end walls and said walls having rims on the upper edges, the rims of said side walls having open parallel recesses therein, one of said compartments having a greater depth than the other, spaced tubular members positioned in the lower part of one of said compartments, provided with upwardly directed spray means, a supply pipe positioned on the outside of said sink, a connection from said supply pipe through the wall of the sink to said tubular members, means clamping said tubular members in position in said compartment, a cover having ribs on side edges thereof slidably mounted on said sink with the ribs positioned in said parallel recesses of the rims of said side walls, spaced perforated tubular members carried by said cover and positioned on the under side of the cover, means temporarily connecting said spaced perforated tubular members of the cover to said supply pipe, a wire basket positioned in the compartment in which the tubular members with the upwardly directed spray means thereon are positioned, and feet carried by the basket and positioned to support the basket above said upwardly directed spray means, said cover adapted to slide over the compartment having the tubular members with the lower spray means thereon substantially closing said compartment.
